UNITED STATES PATENT OFFICE.

MORRIS SHEINMAN, OF NEW YORK, N. Y.

LOCK.

1,398,044.

Specification of Letters Patent.

Patented Nov. 22, 1921.

Application filed June 5, 1920. Serial No. 386,666.

To all whom it may concern:

Be it known that I, MORRIS SHEINMAN, a citizen of the United States of America, residing at New York city, Bronx county, 5 State of New York, have invented certain new and useful Improvements in Locks, of which the following is a full, clear, and exact description.

This invention relates to improvements in locks, more especially locks for doors and the like, one of the objects of my invention being to provide a lock so arranged as to prevent the door from being forced by being lifted upwardly. to accomplish this result, I 10 provide means independent of the bolt of the lock to engage means carried by the frame for the door, preferably on the striker-plate, the engagement of the parts being automatic and in no way dependent upon the bolt or 15 means to actuate the bolt. A further object of the invention is to provide a lock and striker-plate which are located exteriorly of the door and door frame, respectively, said lock having a vertically movable bolt ar- 20 ranged to engage locking elements carried by the striker-plate. The lock and striker plate will of course be located on the inner exterior surface of their respective elements, or in other words on the sides of said ele- 25 ments which are within a room or the like. Further features of improvements will hereinafter appear.

I will now proceed to describe my invention in detail, the novel features of which I 30 will finally claim, reference being had to the accompanying drawing, wherein:—

Figure 1 is a fragmentary view in elevation, illustrating my improved lock mechanism;

Fig. 2 is an enlarged detail view of the lock and striker-plate;

Fig. 3 is an enlarged sectional plan view, the section being taken on a line 3—3 in Fig. 1;

Fig. 4 is an enlarged cross sectional detail view, the section being taken on a line 4—4 in Fig. 3;

Fig. 5 is an enlarged end view, illustrating the striker-plate;

Fig. 6 is an enlarged detail view of the lock, the cover plate being removed;

Fig. 7 is a longitudinal sectional view thereof, the section being taken on a line 7—7 in Fig. 6; and

Fig. 8 is an enlarged fragmentary detail view illustrating my improved mounting for the cylinder lock mechanism.

My improved device consists of a bolt supporting casing 9, which is secured to a door or the like, indicated by 10, and a co- 60 operating striker-plate 11, mounted on the door frame 12. The casing 9 carries a bolt 13 operable by rotatable fingers 14 and 15 which in turn are actuated by a handle or knob 16 secured to the rotatable bushing 17 which carries fingers 14 and 15. The inner end of the shank 18 of the bolt 13 carries a tumbler 19 pivoted at 20 to said bolt, said tumbler being arranged to engage a keeper 21 carried by the casing 9. When the 65 tumbler 19 is in the position indicated in Fig. 6, the bolt cannot be raised. After tumbler 19 has been moved from the position indicated in Fig. 1 to clear the keeper 21, the bolt can be raised (see dotted lines 70 22 in Fig. 2), after which the nose 23 of tumbler 19 will rest upon the keeper 21, thereby preventing the lowering of the bolt 13. The tumbler 19 is actuated to clear the keeper by the finger 14 or finger 15 according 75 to the direction of rotation of knob 16. When knob 16 is rotated in the direction of the arrow in Fig. 6, finger 15 will contact with projection 24 on tumbler 19 and move the latch away from the keeper 21. 80 A continued rotation of the said knob will cause the finger 15 to contact with the projection 25 on the shank 18 of bolt 13 and finally move the bolt in the direction of the arrow 26 in Fig. 6, or to the position indicated by dotted lines in Fig. 2, after which 85 the tumbler 19 will engage the top surface of the keeper 21 and said bolt will be locked against downward movement until the tumbler is again actuated. When the bolt 13 is in the uppermost position, the door 10 may 90 be opened. When knob 16 is turned in the opposite direction, tumbler 19 will be again actuated and the bolt will be moved down, for the reason that the finger will strike the other projection 27 on the shank of the bolt 95 and actuate same. As the knob will be located on the inside of a door, the above operations can take place from within a room only.

To actuate said bolt by a key from the outside, I provide the ordinary cylinder lock mechanism indicated by 28, said mechanism

being connected by the usual plate 29 to a rotatable bushing 30 having a finger 31 to actuate the tumbler 19 and bolt 13 (see Fig. 7).

5 As can be seen in Fig. 6, the bolt 13 is in the form of a T having a head 32 and a guide plate 33 adjacent the head to provide slots 34 to receive the guides 35 carried by the casing 9. The guides 35 are spaced apart 10 to provide a jaw 36 to receive an abutment-block or aliner 37 carried by the striker-plate 38 which is mounted on the face 39 of the frame 12 of the door. In other words, the guides 35 are extended beyond the cover- 15 plate 40 which carries the bushing 30, to overlap the end surface 42 of the door 10 (see Fig. 3). The guides lie against the end surface of the door and are secured to the door by screws 43. The abutment 37 20 projects from the member 44 of the striker-plate to enter between the guides 35 when the door is closed, as indicated in Figs. 3 and 4. The member 45 of the striker-plate, which is disposed in this instance at a right 25 angle to member 44, carries (in this instance) two studs 45 having heads 46 which are larger in diameter than the shanks 47 of said studs. The studs 45 act, in conjunction with bolt 13, to prevent the door from 30 being opened from the outside, unless said bolt is actuated by a key in manner described.

To coöperate with the studs 45, the bolt 13 is provided with openings 48, said openings being made up of a slot 49 having in communication therewith passages 50. The width of the slots 48 slightly exceed the diameter of the shanks 47 of the studs 45, while the passages 50 slightly exceed in 40 diameter the diameter of heads 46 of said studs 45. When bolt 13 is raised as per dotted lines Fig. 2, the heads of the studs 45 and passages 50 will aline, but when the bolt 13 is lowered, or rests in its lowest position, the shanks 47 of the bolts will be engaged by the slots 40, that is to say, when the door is closed and bolt 13 is in its lowermost position, said door cannot be opened, as the heads of the studs will prevent the 50 door from being moved upon its hinges, one being indicated by 51 in Fig. 1. At this time, that is to say, when the door is closed, block 37 on the striker-plate will be located between the guides 35, as indicated in Fig. 55 4; hence the door cannot be forced upwardly thereby causing the bolt 13 to be raised sufficiently to cause the heads of the studs 45 to aline with the passages 50. It will be apparent that the block 37, bolt 13 and studs 60 45 coöperate to prevent the door from being opened unless the lock is actuated by a key from the outside or from the inside by turning knob 16.

The cover plate 40, which carries the bush- 65 ing 30, is secured to the casing 9 by screws

53 and the casing 9 is secured to the door by screws 54. The cover plate 40 carries a lip 55 which engages the forward surface of the guide plate 33. The lip 55 aids to reinforce the bolt 13 to prevent the door from being 70 forced open by an instrument inserted between the door and casing along the edge 56 of said door, or rather it reinforces the casing 9 as any strain on the casing in the direction of arrow 57 will be transmitted to 75 the bolt through the guides 35 and lip 50; hence the lip will reinforce the casing.

To render the cylinder lock 28 adjustable, to accommodate doors of various thicknesses, I provide studs 58 which are carried by the 80 cover plate 40 and extended into an opening 59 formed in the door 10. The studs 58 are notched as at 60 to receive set-screws 61, one only being shown in Fig. 8. The cylinder 28 can be adjusted longitudinally of the 85 studs 58 and secured in adjusted position by the set screws 61, which will engage the notch 60 in alinement therewith. The plate 29 will, of course, be long enough to permit considerable adjustment on the part of the 90 cylinder 28.

What I claim and desire to secure by Letters Patent is:—

1. In a lock mechanism, a striker plate, a projection carried thereby having an enlarged portion, a bolt movable in parallelism with said plate in a vertical plane and having an opening to permit of the passage of the enlarged portion of said projection, said hole having a slot in communication with 95 said passage to engage the smaller portion, of said projection, a casing for said bolt having a jaw, and a projection carried by the striker plate to engage said jaw.

2. In a lock mechanism, a striker plate for 105 the frame of the door, a stud carried thereby, a head carried by the stud, said head being of larger diameter than the shank of the stud, a casing for attachment to a door, a bolt slideable within the casing, and means to actuate 110 the bolt, spaced apart projections carried by the casing, a block carried by the striker plate to lie in the space between said projections when the door is closed, said bolt having an opening consisting of a passage whose 115 diameter is greater than the diameter of the head of said stud and a slot arranged to receive the shank of said stud.

3. In a lock, a slidable bolt having a head and a guide-plate carried thereby but spaced 120 from the head to provide a guide-way and guides carried by the casing to engage the guide-way in said bolt, whereby said bolt is held against withdrawal from said casing, said guides being extended beyond the inner surface of the bolt and arranged for secure- 125 ment to the adjacent end surface of a door.

4. In a lock mechanism, the combination 130 of a striker plate, projections carried there- by, a casing, a bolt carried by the casing en-

gaging certain projections, and a jaw member mounted on the casing to engage another of the projections on the striker plate.

5. In a closure fastener, a headed stud and a member having a keyhole slot for normally freely receiving said stud and shiftable by a key interlocking engagement with the stud.

6. In a closure fastener, a headed stud and a member having keyhole slot for normally freely receiving said stud and shiftable into interlocking engagement with the stud the shifting means requiring a key from the exterior of the closure and manual means for operating the shifting means from the interior of the closure.

7. In a closure fastener, a plurality of headed studs a member provided with a plurality of keyhole slots registering with and normally freely receiving said studs and shiftable by a key into interlocking engagement with the studs.

8. In a closure fastener, a plurality of headed studs, a member provided with a plurality of keyhole slots registering with and for normally freely receiving said studs, means for shifting the slots into engagement with the studs, the shifting means requiring a key from the exterior of the closure and manual means for operating the shifting means from the interior of the closure.

9. In a lock, a striker plate provided with a plurality of headed studs, a bolt provided with a locking tumbler and with a plurality of keyhole slots registering with and for normally freely receiving the studs and shiftable into interlocking engagements with the studs.

10. In a swinging door lock, an angle bar adapted to fit the corner of the door frame, a plurality of bosses mounted on the bar, means mounted on the door for engaging certain of the bosses to prevent movement of

the door and means mounted on the door parallel to the surface of the bar to engage other of the bosses to prevent lateral and swinging movement of the door.

11. In a door lock, a striker plate provided with a pair of faces, a bolt coöperating with one of the faces and an aliner mounted on the other face.

12. In a door lock, a sliding bolt, a casing therefor, the bolt projecting beyond the casing and enlarged exteriorly of the casing, the enlarged portion bearing upon the face of a casing to guide the bolt.

13. In a door lock, a vertically sliding bolt, a casing therefor, a bolt projecting beyond the casing and enlarged exterior of the casing, the enlarged portion bearing upon the casing to guide the bolt, a guide mounted on the bolt and bearing upon the interior of the casing.

14. In a lock, a casing, an I-bolt extending through the casing and guided by the exterior of the casing, a swinging detent on the inner end of the bolt, perforations on the exterior end of the bolt, means for lockingly engaging the perforations and means for moving the bolt parallel to the said exterior guide after movement of the detent.

15. In a door lock, a bolt, a casing for the bolt adapted to be affixed to the door frame with a side co-planar with the edge of the door, a bearing for the bolt adapted to engage both the exterior and interior of said side of the casing to slidably mount the bolt to the casing and resist movement of the bolt longitudinally of the casing.

Signed at New York city, N. Y., this 4 day of June, 1920.

MORRIS SHEINMAN.
